PAGE 2

FIG. 4

FIGURE 1 is a top view of the helicopter toy showing my new design.

FIGURE 2 is a side view of the helicopter toy of FIGURE 1, the side opposite being substantially the same as the side shown.

FIGURE 3 is a front view of the helicopter toy.

FIGURE 4 is a perspective view of the helicopter toy. This application is a division of my prior pending application D. 75,519 filed June 25, 1963, entitled "Aerial Toy."

I claim:

The ornamental design for a helicopter toy, as shown and described.
